(57) **CLAIM**

The ornamental design for a fireplace, as shown and described.

DESCRIPTION

FIG. 1 is a perspective view of a fireplace showing the new design;

FIG. 2 is another perspective view thereof;

FIG. 3 is a perspective view of a tray of the fireplace;

FIG. 4 is another perspective view thereof;

FIG. 5 is a front elevation view thereof;

FIG. 6 is a back elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a perspective view of a base of the fireplace;

FIG. 12 is another perspective view thereof;

FIG. 13 is a front elevation view thereof;

FIG. 14 is a back elevation view thereof;

FIG. 15 is a left side elevation view thereof;

FIG. 16 is a right side elevation view thereof;

FIG. 17 is a top plan view thereof; and,

FIG. 18 is a bottom plan view thereof.

The broken lines depict portions of the fireplace that form no part of the claimed design.

FIGS. 3-10 and FIGS. 11-18 separately depict components of the fireplace to show aspects of the design that are not visible when combined.
